UNITED STATES PATENT OFFICE.

WALTER KEISER, OF ST. LOUIS, MISSOURI, ASSIGNEE TO THE AIR CONDITIONING AND ENGINEERING CO., OF ST. LOUIS, MISSOURI, A CORPORATION.

VENTILATING SYSTEM.

Application filed March 14, 1925. Serial No. 15,560.

My invention relates to improvements in ventilating systems and more particularly to those which are arranged to recirculate air and adapted to employ an air purifying agent.

It is well known that when air is drawn from occupied areas and recirculated that the odors and other deleterious matters which are present are not only obnoxious, but also harmful, and that, in present ventilating practice, it is common to use ozone as the agent with which to make this recirculated air fresh and pure. It is obvious that if ozone is used to accomplish this result that it must at all times be present and at work while recirculation is taking place and that some means must be provided that will automatically insure its supply and presence in the system.

20 The object of my invention is to provide a recirculating ventilating system which employs an ozone generator, and in which ozone is present whenever recirculation takes place. A further object is to provide a means whereby the ozone generator is not dependent on any human agency to put it in operation, but may be automatically started and put in operation by the flow or pressure of recirculated air in the system.

30 My improvements consist in the novel construction, combination, and arrangement of parts hereinafter fully, clearly, and concisely described, definitely pointed out in my claims and illustrated by the accompanying drawing which is a diagrammatical illustration of a portion of a building equipped with a typical recirculating system.

For the purpose of illustrating my invention, I have shown in the accompanying drawing one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

50 1 is a ventilating fan which may be driven by a motor 2 which has any usual starting and stopping means such as the switch 2^a connected to the wires 2^b. 3 is an ozone generator. The fan and generator are preferably in a chamber such as "A", which may

have a heater 4, preferably positioned in one wall, through which air is admitted for introduction into the system and building. 5 is a duct which conveys air from the fan into a room of the building, such as "B", through suitable ducts and openings such as 6 and 7, respectively. 8 is a vent opening through which air is exhausted from the room "B" through the ducts 9 and 10. These ducts communicate with a return duct or vent shaft 60 11 through the opening 12. Communication to the return duct may be cut off, when desired, by a suitably located damper 13. By preference, I also provide a ventilator 14 equipped with a damper 15, located at some 65 suitable portion of the building through which air may be expelled from the building. 16 is an opening for admitting outside air and may be equipped with adjustable dampers 17. 18 is an air operated switch of any 70 suitable design. This switch, which has a balanced air vane 19, is placed in an easily accessible place in any of the ducts or air passages through which recirculated air flows and is actuated or operated by the force or 75 pressure of the moving air against the vane. The movement of this vane opens or closes the electric circuit between the switch and the ozone generator. In this connection I do not wish to be understood as limiting myself to the precise form of switch shown or described, as it is obvious that I may employ any form or type of air-actuated switch which is adapted to respond to the flow of air ordinarily set up in the ducts or passages of a 80 85 ventilating system. 20 and 21 are wires supplying electric current to the switch and the ozone generator.

The operation of my invention is as follows:

When it is desired to recirculate the air in the building, the damper 15 in the ventilator 14 is closed, thus preventing the expulsion of the air to the atmosphere. In this case the damper 13 is opened so that the air can be 90 drawn from the duct 10 into the return duct 11 and thus recirculated. The damper 17 may be closed entirely for complete recirculation or partly opened for partial recirculation. The motor 2 causes the fan 1 to operate, 95 resulting in a circulation of air through ducts 5, 6, 9, 10 and 11, chamber A and room B. Whenever air is drawn through duct 11 it moves the balanced vane 19, causing the switch 18 to complete the electric circuit to 100 105 110

the ozone generator. The air drawn through the duct 11, together with such air as may be admitted through the outside opening 16, passes through the heating coils 4 and into chamber A where ozone is being produced in suitable quantities for purification purposes. The purified air then passes through the fan 1 and into duct 5, where it is carried through the system, being discharged into a room or 10 rooms B, in its course of recirculation. When the fan is stopped, movement of air through the duct 11 ceases, thereby releasing the pressure or force against the vane and allowing it to return to closed position; this breaks 15 the supply circuit to the ozone generator and thus shuts it off.

I claim:

1. A ventilating system having an ozone generator and means adapted to employ moving air to put the ozone generator into operation and stop the ozone generator when air movement ceases.
2. In a ventilating system adapted to recirculate air, means for electrically treating air, and means adapted to employ moving air to bring said air-treating means into operation only while recirculation is in progress.
3. In a ventilating system a fan, air passages, means for electrically treating air, and means adapted to be actuated by the movement of air to secure operation of the air treating means.
4. In a recirculating ventilating system a fan, air passages, an ozone generator, and means adapted to be actuated by the movement of air to secure automatic operation of the ozone generator only when air is recirculated through the system.
5. In a recirculating ventilating system adapted to employ ozone, air actuated means adapted to control the introduction of ozone into the system only when recirculation occurs.
6. A recirculating ventilating system comprising means adapted to generate and intro-

duce ozone, means adapted to recirculate air, and means whereby recirculated air causes the automatic operation of the ozone generating means only when air is being recirculated.

7. In a recirculating ventilating system a fan, an ozone generator, a control for said ozone generator and means whereby the recirculated air actuates said control for the ozone generator.

8. In a recirculating ventilating system, a fan, air passages, an ozone generator, an electric switch adapted to control the circuit to the ozone generator and means adapted to be actuated by air and close said circuit only while air is being recirculated.

9. In a recirculating ventilating system, ducts, means for producing a flow of air through said ducts, an ozone generator having an electric supply circuit connected therewith and means for causing the said flow of air to close the electric supply circuit to said ozone generator.

10. A recirculating ventilating system comprising a fan, ducts, an electric switch, an ozone generator, and means whereby the recirculated air is employed to actuate the switch and supply electric current to said ozone generator while the recirculated air moves through said ducts and cut off said electric current when the movement of said air ceases.

11. A recirculating ventilating system comprising the combination of a fan, air passages, an ozone generator, means for restricting and directing the flow of air through said passages, means for admitting outside air, means for exhausting air to the atmosphere, an electric switch connected with the ozone generator and means connected with said switch whereby said switch is actuated by the force of the air moving through an air passage.
